CLAMPING DEVICE.

Application filed September 16, 1924. Serial No. 738,024.

This invention relates to a clamping device, particularly to a clamping device of the character of a chain pipe vise.

One object of the invention is to provide a novel and improved construction of clamping device which may be operated in a simple, rapid, and convenient manner to efficiently clamp an article between a pair of clamping members one of which comprises a flexible member adapted to extend over the article.

A further object of the invention is to provide a novel and improved vise of the character of a chain pipe vise which may be economically manufactured and rapidly operated in a simple and highly convenient manner.

To these ends the invention consists in the clamping device hereinafter described and particularly defined in the claims at the end of the specification.

In the drawings illustrating the preferred embodiment of the invention, Fig. 1 is a vertical sectional view of a chain pipe vise embodying the features of the present invention: Fig. 2 is an end elevation of the same; Fig. 3 is a side elevation of the same; and Figs. 4 and 5 are sectional details on lines 4—4, 5—5, respectively, of Figs. 1 and 2; and Fig. 6 is a diagrammatic view to be referred to illustrating the clamped action.

Referring to the drawings, the chain pipe vise illustrated therein and embodying the features of the present invention, comprises in general a base or body portion 10 provided with an integral flange portion 12 which is adapted to rest upon and be secured to a supporting surface such as a table 14 as illustrated in Fig. 3, to hold the vise in operative position. The pipe or other article 16 to be clamped is placed upon the base or supporting member 10, to be received within a clamping member or jaw 20 upon the upper surface of the base and which is herein shown as comprising a curved groove having teeth 22 for assisting in the clamping action. The vise is also provided with a flexible clamping member for clamping the pipe or other article 16 against the base or body portion 10 and as herein shown the chain 24 is capable of being extended over the article and to have one end portion 29 thereof secured in fixed relation to the base 10 by a member 30 secured to the base. As

herein shown the chain is preferably constructed with pivot pins 29 projecting beyond each of the links thereof and the member 30 is cast integrally with a depending rear portion 33 of the base 10 and is provided with a pair of hooks 31 spaced apart sufficiently to permit the chain to pass between them and to permit the pins 29 to engage the hooks 31 in the manner illustrated in Fig. 1.

In the operation of the vise, in order to tighten the chain 24 around the pipe or other article 16 to clamp the same against the base 10, the second end portion 28 of the chain 24 is secured to an operating member or handle 40 which operating member is pivoted at 41 upon the base and the point of connection therewith is located at a distance from the pivot 41 so that when the pivoted member 40 is swung about the pivot and into its operative clamping position, the second end portion of the chain is drawn to cause the chain to tighten around the pipe or other article 16 and to clamp it against the base. As herein shown, the second end portion of the chain is arranged to pass between guides comprising a pair of bearing members 44, 46, spaced apart and mounted upon the upper portion of the base 10. The operating member or handle 40 is preferably forked at its inner end, and each portion 47, 48 of the fork is pivoted upon pins 50, 51 secured in reinforced portions of depending side members 52, 53 forming a part of the base 10. The second end portion 28 of the chain is pivotally connected at 39 to one end of a rod 54 which is slidably supported in bearings 56, 57 in the body portion of the operating handle or member 40. The second end of the rod 54 is connected by a spring 58 to the outer end of the operating member or handle 40 so that through the rod 54 and spring 58, the chain 24 is yieldingly connected to the operating member 40 whereby when the operating member is moved from an inoperative to operative clamping position, that is from the full to the dotted line position as illustrated in Fig. 1, the tension in the spring operates to take up the slack in the chain 24 and to tighten it around the pipe or other article 16 to be clamped.

Provision is made for securing the chain 24 in fixed relation to the operating handle or member 40 when the latter has moved through a portion of its stroke and after

the slack in the chain has been taken up, so that thereafter as the operating handle or member 40 is moved into its operative clamping position, the chain is positively drawn tightly around the pipe or article 16 and operates to clamp it against the base 10. For this purpose the intermediate portion of the rod 54 is threaded and a split nut 60 is slidably mounted in suitably shaped openings in the operating handle or member 40 to be capable of movement into and out of engagement with the threaded portion of the rod 54. The split nut 60 is normally held in a position out of engagement with the threaded portion of the rod 54 by spring members 62, 63, secured to opposite sides of the operating handle or member 40 as illustrated in Fig. 3. A cam member 65, preferably adjustably mounted upon the base 10 is positioned to engage the split nut 60 when the operating handle or member 40 has reached a predetermined point in its movement toward its operative clamping position. As herein shown the cam member 65 comprises a U-shaped piece secured within the lower portion of the base 10 and between the depending rear member 33 and the depending side members 52, 53, by bolts 70 extended through slots 71 in each of the depending side members 52, 53 as illustrated in Fig. 2. With this construction, the cam member 65 may be adjusted transversely of the base 10 to position it so it will engage the split nut 60 at the desired point in the descent of the operating handle or member 40. In order to facilitate the adjustment of the cam member 65 an adjusting screw 74 is screwed through the rear member 32 of the base 10 and is secured to the cam member 65 by a lock nut 75 and pin 76 as shown in Fig. 1. With this construction, therefore, when the operator pushes down the operating handle or member 40 from the horizontal position as illustrated in Fig. 2 toward a vertical position, the jaws of the cam member 65 engage the split nut 60 when the handle 40 has reached a predetermined point as illustrated in Fig. 1, forcing the portions of the split nut 60 toward each other and into engagement with the threaded portion of the rod 54, thus securely locking the rod 54, and consequently the chain 24, in fixed relation to the operating handle or member 40. As the operator continues to depress the handle 40 into the vertical position, the pivotal point 39 at which the end of the chain 24 is connected to the end of the rod 54 is caused to move in an arc about the pivot 41 of the operating handle or member 40 upon the base as a center, thus drawing out the chain and causing it to tightly engage the pipe or article 16 and to clamp the latter between the chain and the upper surface of the base 10. The movement of the pivotal point 39 is illustrated in the diagram shown

in Fig. 6, and the distance represented as 78 therein is the amount that the chain is drawn out during the final clamping action.

In the vertical or operative clamping position of the operating handle or member 40, it will be observed that the pivotal point 39 at which the chain 24 is connected to the operating handle 40 is brought into alignment with the pivot 41 of the handle upon the base, so that the tendency of the chain 24 to move the handle 40 from its operative clamping position is rendered ineffective by the alignment of the pivots in this manner so that the effect of the stress exerted by the chain 24 upon the handle 40 has no 80 rotatable effect upon the handle.

It will also be observed that the present construction of clamping device may be operated very rapidly, the operator merely passing the chain over the pipe or other article and affixing it to the hooks 31 and thereafter depressing the handle 40 into a vertical position. To unclamp the pipe or other article, the operator merely raises the handle into the horizontal position, and unhooks the chain.

While the preferred embodiment of the invention has been illustrated and described, it will be understood that the invention may be embodied in other forms within the scope 95 of the following claims.

What is claimed is:

1. In a vise of the character described, in combination, a base provided with a clamping member, a chain adapted to extend over the article to be clamped, and means for tightening the chain to clamp the article against the clamping member upon the base, including a fixed member for holding one end portion of the chain and a pivoted member adapted to yieldably take up the slack in the chain upon movement of the pivoted member through a portion of its stroke, and means for rigidly connecting at a distance from the pivot the second end portion of the chain with the pivoted member before the pivoted member reaches its final operative clamping position.

2. In a vise of the character described, in combination, a base provided with a clamping member, a chain adapted to extend over the article to be clamped, and means for tightening the chain to clamp the article against the clamping member upon the base, including a fixed member for holding one end portion of the chain, a pivoted member, a yieldable connection between the second end portion of the chain and the pivoted member adapted to take up the slack in the chain upon movement of the pivoted member through a portion of its stroke, and means for rigidly connecting at a distance from the pivot the second end portion of the chain with the pivoted member when the pivoted member reaches a predetermined 120

position in its movement into final operative clamping position.

3. In a vise of the character described, in combination, a base provided with a clamping member, a chain adapted to extend over the article to be clamped, and means for tightening the chain to clamp the article against the clamping member upon the base, including a member secured to the base for holding one end portion of the chain, a second member pivoted upon the base, a yieldable connection between the second end portion of the chain and said pivoted member comprising a threaded rod slidably mounted in said pivoted member and connected at one end to the chain, a spring connecting the second end of the rod to the pivoted member whereby as the pivoted member is moved towards its operative clamping position the spring and rod yieldingly take up the slack in the chain, and means for rigidly connecting the threaded rod to the pivoted member when the latter has reached a predetermined point in its movement toward its final operative clamping position.

4. In a vise of the character described, in combination, a base provided with a clamping member, a chain adapted to extend over the article to be clamped, and means for tightening the chain to clamp the article against the clamping member upon the base, including a member secured to the base for holding one end portion of the chain, a second member pivoted upon the base, a yieldable connection between the second end portion of the chain and said pivoted member comprising a threaded rod slidably mounted in said pivoted member and connected at one end of the chain, a spring connecting the second end of the rod to the pivoted member whereby as the pivoted member is moved toward its operative clamping position the spring and rod yieldingly take up the slack in the chain, and means for rigidly connecting the threaded rod to the pivoted member when the latter has reached a predetermined point in its movement toward its operative clamping position, said means including a split nut movably mounted in the pivoted member and a cam member upon the base adapted to engage the nut.

5. In a vise of the character described, in combination, a base provided with a clamping member, a flexible clamping member adapted to extend over the article to be clamped and means for tightening said flexible member around the article to clamp it against the clamp member upon the base, including a fixed member for holding one end portion of the flexible member, a member pivoted upon the base and to which the second end portion of the flexible member is fastened at a distance from the pivot,

guide members upon the base between which a portion of the flexible member extends whereby the alignment of the flexible member between said guides with the pivot for the pivoted member and the point at which the flexible member is connected to said pivoted member serves to lock the pivoted member in an operative clamping position.

6. In a vise of the character described, in combination, a base provided with a clamping member, a flexible member adapted to extend over the article to be clamped and means for tightening the flexible member around the article to clamp it against the clamp member upon the base, including a fixed member for holding one end portion of the chain, a pivoted member, a yieldable connection between the second end portion of the chain and said pivoted member and adjustable means for rigidly securing the second end portion of the flexible member to the pivoted member at a predetermined point in the movement of the pivoted member.

7. The combination with a clamping base of a flexible clamping member cooperating therewith and adapted to extend over the article to be clamped and means for tightening the flexible clamping member to clamp the member against said base, including means for holding one end portion of the flexible clamping member from movement, a pivoted member to which the second end portion of a flexible clamping member is yieldingly secured and means for rigidly securing the second end portion of the flexible clamping member to the pivoted member at a predetermined point in the movement of the latter into operative clamping position.

8. In a vise of the character described, in combination a base, a flexible clamping member adapted to extend over the article to be clamped, a pivot lever, said pivot lever having a yieldable connection with one end of said flexible clamping member adapted to take up slack in said flexible member during at least a portion of the movement of said pivot lever, the other end of said flexible element being fixedly secured to said base.

9. A vise of the character described, in combination, a base, a flexible clamping member adapted to extend over the article to be clamped on said base, one end of the flexible member being fixedly secured with respect to the base, a pivot lever, a resilient connection between said pivotal lever and the other end of said flexible clamping member, said resilient connection serving to take up slack in said flexible member during at least a portion of the operative movement of said pivoted lever, and means for rigidly securing the end of the flexible clamping element to the pivoted lever as the pivoted lever approaches its final operative clamping position.

10. In a vise of the character described, in

combination, a base, a flexible clamping member adapted to extend over the article to be clamped on said base, one end of said flexible member being fixedly secured with respect to the base, a pivoted lever associated with said base, a resilient connection between the other end of said flexible clamping member and said pivoted lever for taking up slack in said chain during a portion of the operative stroke of said lever, means for

rigidly securing the flexible clamping element to said lever operative only upon the final portion of the stroke of said lever, said means comprising devices associated with said base and engageable with said handle when the handle approaches its said final operative stroke. 15
